UNITED STATES PATENT OFFICE

154,932

DESIGN FOR AN ELASTIC FABRIC

Gerhard Knorr, New York, N. Y.

Application October 30, 1948, Serial No. 149,402

Term of patent 3½ years

(Cl. D92—1)

To all whom it may concern:

Be it known that I, Gerhard Knorr, a citizen of the United States, residing in the city of New York, county of New York, and State of New York, have invented a new, original, and ornamental Design for an Elastic Fabric, of which the following is a specification, reference being had to the accompanying drawing, forming a part thereof.

The figure of the drawing is a plan view of an elastic fabric, showing my new design.

The broken lines outline a design unit, which unit is repeated over the fabric in regular succession as indicated by the extensions beyond the unit boundaries.

I claim:

The ornamental design for an elastic fabric, as shown and described.

GERHARD KNORR.
